UNITED STATES PATENT OFFICE.

SIGMUND STERNAU, OF NEW YORK, N. Y., ASSIGNOR TO S. STERNAU & COMPANY, OF NEW YORK, N. Y., A COPARTNERSHIP.

DESIGN FOR A WASHRAG OR TOWEL HOLDER.

43,289.

Specification for Design.

Patented Nov. 26, 1912.

Application filed July 11, 1910. Serial No. 571,507. Term of patent 7 years.

To all whom it may concern:

Be it known that I, SIGMUND STERNAU, a citizen of the United States, and a resident of the borough of Manhattan, city, county, and State of New York, have invented a new, original, and ornamental Design for a Washrag or Towel Holder, of which the following is a specification, reference being had to the accompanying drawing, forming a part thereof.

The drawing is a perspective view of a wash rag or towel holder showing my new design.

The design comprises a plate with curved extremities. Upon the plate are a series of

hooks of the shape shown, the plate at the base of the hooks being curved outward, the bases of the hooks being curved to correspond to the curved portions of plate as shown.

The design resides in the shape of the plate, the curved portions thereof at the base of the hooks, and the hooks themselves.

I claim:

The ornamental design for a wash rag or towel holder, as shown and described.

SIGMUND STERNAU.
